TOY BANK

Harry E. Gosselin, Bridgeport, Conn.

Application August 13, 1952, Serial No. 304,110

4 Claims. (Cl. 232—4)

The present invention relates to banks and particularly to small banks such as may be used as a promotion item or gift.

It is an object of the invention to provide a bank which is of simple construction and operation and one which can be made cheaply enough to be a "give away" item.

Another object of the invention is to provide a bank having advertising indicia which is located adjacent a coin-receiving slot and money-removing opening so that the indicia will be in a position to be viewed whenever the bank is used. Another object of the invention is to provide a compartmented bank whereby small coins and large coins and bills may be segregated.

These objects are accomplished by providing a bank with a hollow base and mounting on the base a simulated building, each of which may, if desired, comprise a compartment of the bank with one receiving only small coins and the other receiving the large coins.

In accordance with the present invention the base and building are preferably formed of plastic material so that it can be readily molded and produced in volume.

A feature of the invention resides in forming the closure for the money-removing opening in the base with a notch along one edge which cooperates with the edge of the opening to provide the coin-receiving slot.

Other objects and advantages of the invention will be apparent from the specification and claims when considered in connection with the drawings in which:

Figure 1 is a top view of the device.

Fig. 2 is an end view of the device.

Fig. 3 is a detailed end view of the base with the closure removed.

Fig. 4 is a sectional view along lines 4—4 of Fig. 2.

Fig. 5 is a detailed view of the garage door in the building through which the coins may be removed.

As shown in the drawings, there is provided a hollow base 10 having mounted on the top surface thereof a simulated building 11 arranged to overlie a part only of the top surface. The building may be of any design but in the illustrated form of the invention it is shown as a cottage.

The base comprises an upper section consisting of the top 12 and sides 13 and a bottom section 14 secured to the sides and forming a hollow money-receiving compartment.

The top surface of the base around the building is provided with suitable simulated landscaping. While this landscaping may be applied to the top in many ways, in the herein illustrated form of the invention it is formed directly on the top to simulate grass 10a, a flagstone walk 10b and driveway 10c to the garage as shown in Fig. 1.

A feature of the invention resides in having an opening 15 in the side 13 of the base through which money deposited in the base may be removed and providing a closure 16 slidably mounted on the base to close said opening.

In the preferred form of the invention the closure is provided with projecting ribs 17 on the side edges which

2

are slidably received in grooves 18 formed on the base. Along one side edge of the closure is an elongate notch 19 which cooperates with the adjacent edge of the opening to form a large coin-receiving slot 20 through which large coins and bills may be deposited in the base. This arrangement greatly facilitates the manufacturing since a separate slot in the base is not required.

On the outer surface of the closure there is a recess 21 to receive a fingernail or an implement to assist in sliding the closure to open position.

When the device is to be used as a promotional item, it is at present preferred to provide on the top surface of the base a smooth indicia-receiving portion 22 wherein suitable advertising indicia 23, such as the name of the bank or real estate office giving out the device, may be inserted. This indicia-receiving space is preferably located on the top adjacent the opening in the base so that when the coins are deposited in the base or removed from the base the indicia will be in position to be readily observed.

If desired the bank may be utilized to segregate large and small coins. This is accomplished by forming the building as a hollow compartment and providing therein a short coin-receiving slot 24 which is located in the chimney 25 and is smaller than slot 20 whereby only small coins may be deposited in the building. The garage door 26 for the building is slidably mounted in grooves 27, as shown in Fig. 5, so that the small coins can be removed from the building. With this relation between the base slot 20 and the slot 24 in the building it will be apparent that large and small coins can be readily segregated if desired in each compartment.

While the bank of the present invention may be made of any suitable material, it is at present preferred to make it of an assembly of molded plastic parts inasmuch as this will permit large scale production at a minimum of cost. Furthermore, by using plastics a wide variety of color combinations may be produced to greatly enhance the appearance of the bank.

Variations and modifications may be made within the scope of the claims and portions of the improvements may be used without others.

I claim:

1. In a bank of the type described, a hollow base member; a simulated building mounted on the top of the base to partially overlie said top, the top of the base adjacent the building having thereon simulated landscaping, said base having an opening in the side thereof through which money deposited in the base may be removed; and a closure slidably mounted on the base to close said opening and having a notch in one edge to form with the edge of the opening a coin-receiving slot through which money may be deposited in the base.

2. In a bank of the type described, a hollow base member; a simulated building mounted on the top of the base to partially overlie said top, the top of the base adjacent the building having thereon simulated landscaping and an indicia-receiving space, said base having an opening in the side thereof adjacent said indicia-receiving space through which money deposited in the base may be removed; a closure to close said opening, and means on opposed edges of the closure cooperating with the edges of the opening to slidably mount the closure thereon, said closure having a notch in one of said edges to form with the edge of the opening a coin-receiving slot through which money may be deposited in the base.

3. In a bank of the type described, a molded hollow plastic base member; a simulated building of molded plastic mounted on the top of the base to partially overlie said top, the top of the base adjacent the building having molded thereon simulated landscaping, said base

70

having an opening in the side thereof through which money deposited in the base may be removed; a plastic closure having means on the opposed edges slidably mounting the closure on the base to close said opening and having a notch in one of said edges to form with the edge of the opening a coin-receiving slot through which money may be deposited in the base; and means on the front surface forming a grip whereby the closure may be moved from closed to open position.

4. In a compartmented bank of the type described, a 10 hollow base member; a hollow simulated building mounted on the top of the base to partially overlie said top and having a short slot therein to receive only small coins and means for removing the coins therefrom, the top of 15 the base adjacent the building having formed thereon simulated landscaping, said base having an opening in the

side thereof through which money deposited in the base may be removed; and a closure having means on the opposed edges slidably mounting the closure on the base to close said opening and having a notch in one of said edges to form with the edge of the opening a coin-receiving slot longer than the slot in the building and through which large coins may be deposited in the base whereby the large coins and small coins can be segregated.
